UNITED STATES PATENT OFFICE.

WARREN J. BAKER, OF SALEM, OHIO, ASSIGNOR OF ONE-HALF TO ANANIAS FRANTZ, OF SAME PLACE.

POST FOR WIRE FENCES.

SPECIFICATION forming part of Letters Patent No. 546,000, dated September 10, 1895.

Application filed May 13, 1895. Serial No. 549,035. (No model.)

To all whom it may concern:

Be it known that I, WARREN J. BAKER, a citizen of the United States, residing at Salem, in the county of Montgomery and State 5 of Ohio, have invented certain new and useful Improvements in Wire-Fence Posts; and I do hereby declare that the following is a full, clear, and exact description of the invention, which will enable others skilled in 10 the art to which it appertains to make and use the same, reference being had to the accompanying drawings, and to the letters and numerals of reference marked thereon, which form a part of this specification.

15 My invention relates to improvements in wire-fence posts, the features of which will be fully hereinafter described and claimed.

The object of my invention is to provide a wide base for the post and so brace the same 20 that the tension of the runners will tend to hold the parts of the base quite rigidly in line.

I accomplish the object by the construction illustrated in the accompanying drawing, in which the figure is a side view of the post and 25 attached parts.

The letters and numerals of reference designate the respective parts.

My purpose is to construct the post and all other parts of iron bars; but some of the parts— 30 as the post and cross-piece at the base—may be of wood.

The post A comprises two metallic bars, and their lower ends are turned and bolted to the cross-piece J. To the ends of this cross- 35 piece are bolted the bars G, H, E, and F. To the outer ends of said bars G and H is bolted the diagonal brace C, and to the outer ends, on the opposite side of the post, is bolted the diagonal brace D. To the rear of this brace,

on the brace C, is attached the diagonal brace 40 B by the bolt S, and the upper end is secured by a bolt to the post near the top. The stay I is used to secure the several runners 1, which are fastened by the staples 2. The runners may be secured to the post by any of 45 the well-known means for this purpose. The combination of the braces C, B, and D is such that the tension of the runners incline the post, causing a downward pressure on the outer end of the base by depressing the stay 50 B, and thereby tending to hold the base parts in line. The base may be secured by being buried beneath the soil, by weights of stone, or by driving pins into the soil over the parts of the base.

Having fully described my invention, what I claim, and desire to secure by Letters Patent, is—

In a wire fence post, the combination of the vertical post A, the cross-bar J attached to 60 the lower end of said post, the horizontal base bars G and H; and the bars E and F forming acute angles, and joined at their inner ends to said cross-bar to complete the base, the diagonal braces C and D attached 65 to the outer angles of said base, and the brace B attached to the post near the top and to the brace C near the junction of the former two, to hold both ends of the base down as the result of the tension on the runners, substantially as described.

In testimony that I claim the foregoing as my own I affix my signature in presence of two witnesses.

WARREN J. BAKER.
